UNITED STATES PATENT OFFICE

167,306

LADY'S STOCKING

Ernest Albin Drechsel, Doylestown, Pa., assignor
to Victor Silk Hosiery Co., New Britain, Pa., a corporation of Pennsylvania

Application February 27, 1952, Serial No. 18,684

Term of patent 14 years

(Cl. D47—7)

To all whom it may concern:

Be it known that I, Ernest Albin Drechsel, a citizen of the United States, residing at Doylestown, county of Bucks, and Commonwealth of Pennsylvania, have invented a new, original, and ornamental Design for a Lady's Stocking, of which the following is a specification, reference being had to the accompanying drawing, wherein:

Figure 1 is a side view of a lady's stocking, embodying the design of this invention with the upper portion of the stocking being illustrated as folded; and,

Figure 2 is a fragmentary rear view taken normal to the showing of Figure 1, and illustrating the heel and leg portion of the stocking immediately thereabove.

I claim:

The ornamental design for a lady's stocking, as shown.

ERNEST ALBIN DRECHSEL.
